FIG. 3

Inventor

THOS. A. HILLIARD

Milton S. Grandaill,

Attorney

UNITED STATES PATENT OFFICE.

THOMAS A. HILLIARD, OF SIOUX CITY, IOWA.

POCKET-RECEPTACLE FOR LIGHTED CIGARS.

1,238,914.

Specification of Letters Patent.

Patented Sept. 4, 1917.

Application filed April 14, 1916. Serial No. 91,218.

To all whom it may concern:

Be it known that I, THOMAS A. HILLIARD, a citizen of the United States, and a resident of Sioux City, in the county of Woodbury and State of Iowa, have invented certain new and useful Improvements in Pocket-Receptacles for Lighted Cigars, of which the following is a specification.

The present invention relates to receptacles for lighted cigars.

The invention has for its primary object the production of an improved receptacle for lighted cigars, that obviates the necessity of destroying a freshly lighted cigar upon entering a public building or street car or upon other occasions when smoking is prohibited.

Another object of the invention is the production of an improved lighted cigar holder to be carried, without inconvenience in the vest pocket, and into which a lighted cigar may be readily inserted.

Still another object of the invention is the production of an improved lighted cigar holder, inexpensive in manufacture and thoroughly efficient in use.

With these and other objects in view, the invention will be fully understood from the following description, reference being had to the accompanying drawing which forms a part of this application, and in which like characters of reference indicate corresponding parts throughout the several views, of which:

Figure 1 is a front elevation of a lighted cigar holder constructed in accordance with the invention.

Fig. 2 is a vertical section of the same, and

Fig. 3 is a fragmentary front elevation with a cigar inclosed therein as when in use.

Referring now to the illustrations, 4 and 5 are front and rear walls respectively, of leather, paper, fabric or other suitable material, and having their side and bottom edges secured together to form a pocket or pouch.

The walls are lined with asbestos or other suitable flexible, fireproof material, 6. The upper ends of the rear wall and its lining, 50 extend a distance above the companion wall and the upper portion of the rear wall folds forwardly and downwardly over the rear wall lining and is glued or otherwise secured to the latter, as at 7. The upper edge

of the front wall is preferably curved downwardly from the side edges, as at 8, to permit convenient removal of a cigar. The upper edge of the front wall is folded rearwardly and downwardly over its lining and is glued or otherwise secured thereto, as at 9.

The cigar is introduced into the holder, lighted end first, the receptacle being readily opened to receive the cigar by pressing the side edges of the case toward each other. The upper end of the rear wall serves as a shield for preventing the butt of the cigar from staining the wearing apparel. It will be observed that the walls of the receptacle impinge and hold the cigar in any position it is therein placed.

Obviously, the cigar may be removed from the receptacle, without removing the receptacle from the pocket, and ashes which may accumulate in the receptacle may be conveniently dumped.

Normally the walls of the device lie flat against each other, making the device very convenient and not the least clumsy in the pocket.

Having thus described my invention, what I claim as new and desire to secure by Letters Patent of the United States is:

1. A lighted cigar-holder comprising a pouch including front and rear walls of flexible material, having their side and bottom edges joined, the upper edge of the rear wall being extended upwardly a distance above the front wall, and asbestos linings for the walls.

2. A lighted cigar-holder, comprising a pouch, including front and rear walls of flexible material and having their side and bottom edges joined, the upper end of the rear wall being extended a distance above the front wall, and an asbestos lining for the walls, the upper ends of said walls being folded inwardly and downwardly and joined to the adjacent faces of the lining.

3. A lighted cigar-holder comprising a pouch including front and rear integral and fire-proof lined walls of flexible material adapted to impinge a cigar and thereby retain the same in spaced relation to the bottom of the receptacle, and adapted to normally lie flat, each against the other.

In testimony whereof I have hereunto set my hand.

THOMAS A. HILLIARD.
